RICHARD S. BRYANT, OF CLEVELAND, OHIO, ASSIGNOR TO THE STANDARD WELDING COMPANY, OF CLEVELAND, OHIO, A CORPORATION OF OHIO.

VEHICLE-WHEEL WITH DEMOUNTABLE RIM.

1153481

Specification of Letters Patent. Patented Sept. 14, 1915.

Application filed November 13, 1914. Serial No. 871,876.

To all whom it may concern:

Be it known that I, RICHARD S. BRYANT, a citizen of the United States, and a resident of Cleveland, county of Cuyahoga, and State of Ohio, have invented a new and useful Improvement in Vehicle-Wheels with Demountable Rims, of which the following is a specification, the principle of the invention being herein explained and the best mode in which I have contemplated applying that principle, so as to distinguish it from other inventions.

from other inventions.

In connection with demountable tire-supporting rims of the kind now very generally used on automobiles, a characteristic feature of construction is the "driver," as it is called, whereby such demountable rim is held against circumferential movement on the felly, or rather felly-band. The wedging or clamping means, of one kind or another, which are used to secure such rim laterally in place on the wheel felly, cannot of course be relied on to prevent this circumferential movement, and it has accordingly been the practice to weld or rivet a transverse plate on the inner face of the rim and to similarly weld or rivet two spaced plates on the outer face of the felly band, the distance between such last-named plates being just sufficient to accommodate the plate on the rim. Usually, moreover, the valve-stem aperture in the rim passes through the attached plate, and the aperture in the felly designed to register therewith hence is located between the two plates on such felly band. Thus these driving plates serve at the same time to non-rotatably secure the rim to the felly band, and as a means for securing registration of these apertures.

40 The object of the present invention is to avoid the necessity of welding separate plates onto the felly band for use in the aforesaid connection, by stamping or embossing lugs of proper form and disposition
45 to serve the same purpose, it being remembered that a considerable strain may be imposed on such lugs.

To the accomplishment of the foregoing and related ends, said invention consists of 50 the means hereinafter fully described and particularly pointed out in the claims.

The annexed drawing and the following de-

scription set forth in detail certain mechanism embodying the invention, such disclosed means constituting, however, but one of various mechanical forms in which the principle of the invention may be used. 55

In said annexed drawing: Figure 1 is a longitudinal section on a median line of a felly-band embodying my present improvements, with a tire-supporting rim shown mounted thereon; Fig. 2 is a transverse section of such band and rim, the latter being illustrated in connection with the felly proper, the plane of the section being indicated by the line 2—2, Fig. 1; Fig. 3 is a section similar to Fig. 2, but taken on the plane indicated by the line 3—3, Fig. 1; Fig. 4 is a perspective view of a section of the felly band by itself; and Fig. 5 is a similar perspective view of the inside of the tire-supporting rim adapted to be mounted upon such felly band.

The general form and construction of felly band 1 require no remark, such band having, as usual, on its one side a beveled flange 2 adapted to receive the corresponding edge of the tire-supporting rim 3, the latter here illustrated as designed for the reception of a straight-sided tire. Such rim is secured in place sidewise on the felly-band by the use of one or more wedge members 4, a plurality of these being intended to be used in the construction illustrated. Such wedges are forced between the band and the other edge of such rim by means of clamp-nuts 5 threaded on bolts 6 that extend transversely of the felly 7, as will be readily understood. These wedges, however, as previously explained, cannot be relied upon to retain the rim against the tendency to rotate around the felly band under driving conditions. The rim is accordingly provided, preferably at the point where the flange-stem aperture 8 is formed therein, with a driving-plate or lug 9 that is welded or riveted to its inner face so as to be substantially integral with the rim. (See Figs. 1 and 5.) Instead, however, of similarly welding or riveting spaced plates or lugs on the felly band to engage or interlock with this driving plate on the rim, I stamp up or emboss the metal of the band on opposite sides of the corresponding valve-stem aperture 10 in

such band so as to form lugs 11 of the form clearly shown in Figs. 1, 2 and 4, said lugs being identical in form but oppositely disposed with reference to such aperture. The dies, whereby these lugs are formed, are constructed to cut entirely through the band on the transverse edge of the lug nearest the hole, and the metal displaced or forced radially outward in amount approximately 10 equal to the thickness of the band, thereby providing an abrupt engaging face or shoulder 12, which is adapted to engage with the opposed face of the driving plate on the rim, when the latter is mounted on the felly band. 15 The die, however, does not cut the metal along the other edge 13 of the section thus upset to form the lug but simply deforms it, and similarly simply deforms or stretches the metal along the two ends 14 of the lug, 20 so that such lug remains integrally attached to the rim along all three such last named edges. The driving strain received on the abrupt edge 12 of the lug is thus taken up by the body of the band, and any tendency 25 of the lug to turn up under such strain is prevented by the manner in which its ends are tied to the band. Accordingly these lugs are even stronger than the separate plates attached to the face of the band, unless the 30 latter are made of considerable size and strongly welded or riveted fast. At the same time the lugs, being directly stamped out of the material of the band, not only economize in metal, but permit of much more rapid and 35 economical manufacture than where separate plates require to be located and thus welded or riveted, as need not be further explained.

Other modes of applying the principle of my invention may be employed instead of 40 the one explained, change being made as regards the mechanism herein disclosed, provided the means stated by any of the following claims or the equivalent of such 45 stated means be employed.

45 I therefore particularly point out and distinctly claim as my invention:—

1. As an article of manufacture, a band for vehicle wheels of the demountable rim class, said band being provided with two 50 similar, spaced driving lugs, stamped up from and integral with the material of said band, said lugs being severed from said band along their juxtaposed edges so as to form abrupt shoulders, substantially as de- 55 scribed.

2. As an article of manufacture, a band for vehicle wheels of the demountable rim class, said band being provided with two 60 similar, spaced driving lugs, stamped up from and integral with the material of said band, said lugs being severed from said band along their juxtaposed edges so as to form abrupt shoulders, and remaining at- 65 tached to said band along their remaining edges, substantially as described.

3. In a vehicle wheel, the combination with the wheel-felly and the felly-band thereon; of a demountable rim adapted to be fitted around said felly-band and pro- 70 vided with a driving plate on its inner face, said felly band being provided with two spaced driving lugs adapted to interlock with said plate, said lugs being stamped up from and integral with the material of said band, substantially as described. 75

4. In a vehicle wheel, the combination with the wheel-felly and the felly-band thereon; of a demountable rim adapted to be fitted around said felly-band and pro- 80 vided with a driving plate on its inner face, said felly band being provided with two similar spaced driving lugs, stamped up from and integral with the material of said band, said lugs being severed from said band along their juxtaposed edges so as to 85 form abrupt shoulders, substantially as de- scribed.

5. In a vehicle wheel, the combination with the wheel-felly and the felly-band thereon; of a demountable rim adapted to 90 be fitted around said felly-band and pro- vided with a driving plate on its inner face, said felly band being provided with two similar spaced driving lugs, stamped up from and integral with the material of said 95 band, said lugs being severed from said band along their juxtaposed edges so as to form abrupt shoulders, and remaining at- tached to said band along their remaining edges, substantially as described. 100

6. As an article of manufacture, a band for vehicle wheels of the demountable rim class, said band being provided with a driv- 105 ing lug, stamped up from and integral with the material of said band, said lug having a transverse edge severed from said band so as to form an abrupt shoulder, substan- tially as described.

7. As an article of manufacture, a band for vehicle wheels of the demountable rim class, said band being provided with a driv- 110 ing lug, stamped up from and integral with the material of said band, said lug having a transverse edge severed from said band so as to form an abrupt shoulder, and remain- 115 ing attached to said band along its remaining edges substantially as described.

8. In a vehicle wheel, the combination with the wheel-felly and the felly-band there- 120 on; of a demountable rim adapted to be fitted around said felly-band, one of said members being provided with a driving plate on its juxtaposed face and the other member being provided with two spaced driving lugs adapted to interlock with said plate, said lugs being stamped up from and integral with the material of said member, substantially as described. 125

9. In a vehicle wheel, the combination with the wheel-felly and the felly-band there- 130

on; of a demountable rim adapted to be fitted around said felly-band, one of said members being provided with a driving plate on its juxtaposed face and the other member being provided with two spaced driving lugs, stamped up from and integral with the material of said member, said lugs being severed from said member along their

juxtaposed edges so as to form abrupt shoulders, substantially as described. ¹⁰
Signed by me, this 10th day of November, 1914.
